UNITED STATES PATENT OFFICE

GEORGE H. MESSEY, OF NEWARK, NEW JERSEY

PUMP AND STRAINER

Application filed September 13, 1929. Serial No. 392,287.

This invention relates in general to pumps and strainers, one object of the invention being to provide a novel and improved combination of a pump and a strainer which shall be simple, inexpensive and compact in construction and efficient and substantially noiseless in operation.

Another object is to provide a novel and improved strainer which is constantly rotated during operation so as to centrifugally throw off or deflect solid particles and prevent them from passing through the strainer.

Other objects are to provide a combined pump and strainer wherein the strainer is arranged in the outlet chamber of the pump and liquid is forced through the strainer into the outlet passage which is formed by a rotatable tubular driving shaft upon which the strainer is mounted so as to rotate therewith; to provide a rotary gear pump wherein the intermeshing gear pistons are driven by a pinion on a tubular shaft which also serves as an outlet for the pump; and to obtain other advantages and results as will be brought out by the following description.

Referring to the accompanying drawings in which corresponding and like parts are designated throughout the several views by the same reference characters:

Figure 1 is an end elevation of a pump embodying my invention.

Figure 2 is a side elevation thereof.

Figure 3 is an enlarged side elevation of the pump with one section of the casing removed, portions being broken away and shown in section.

Figure 4 is a transverse vertical sectional view on the line 4-4 of Figure 3.

Figure 5 is a similar view on the line 5-5 of Figure 3.

Figure 6 is a transverse vertical sectional view on the line 6-6 of Figure 5.

Figure 7 is a detached side elevation of the strainer and

Figure 8 is an enlarged transverse vertical sectional view through one of the gear pistons and its mounting.

Specifically describing the illustrated embodiment of the invention, the pump comprises a casing formed of the sections A and

B which are separably connected by cap screws or the like 1. One of the casing sections, in the present instance the section A, has a pump chamber 2 formed therein in which are journaled a pair of intermeshing gear pistons 3 and 4. The pump chamber has an inlet passage 5 at one side of the pistons 3 and 4 to which is connected an inlet pipe 6. At the other side of the pump pistons is an outlet chamber 7 from which leads a passage 9 to which may be connected a pressure gauge 10. Another passage 11 also communicates with the outlet chamber and has connected thereto a pressure relief valve 12 to which is in turn connected an overflow 65 or return pipe 13.

For driving the gear pistons 3 and 4 I may utilize a pinion 14 which is arranged in the outlet chamber 7 and rigidly secured as by a key 15 to one end of a tubular shaft 16 which extends through an opening 17 in the casing section A into the outlet chamber. This shaft 16 may comprise the shaft of an electric motor or other suitable source of power 18. Interposed between the pinion 14 and the adjacent inner surface of the casing section A is a hardened steel washer 19, and surrounding the shaft 16 is a packing gland 20 to prevent leakage of the liquid out of the opening 17. Preferably a passage 21 is provided in the casing section A to establish communication between the inlet 5 and the opening 17.

The casing section B has a plurality of openings 22 for establishing communication between the outlet chamber 7 and the outlet or strainer casing 23. This outlet casing may comprise a cup-like chamber 24 secured by screws 25 to the outside of the casing section substantially coaxially with the end of the shaft 16 which also projects through the casing section B into the outlet casing. A strainer 26 is secured upon the end of the tubular shaft 16 to rotate therewith, and this strainer may comprise a hollow body 27 circular in cross-section having screw threads for securing it upon the shaft. The body is provided with a plurality of circumferential grooves 28 at the bases of which are openings 29 leading into the interior of the

body which communicates with the passage through the tubular shaft 16. Secured to the body exteriorly thereof is a wire mesh covering 30.

5 With this construction it will be observed that upon rotation of the shaft 16 by the motor 18, the gear pistons 3 and 4 will be driven in the direction of the arrows on Figure 3 by the pinion 14. This will draw liquid into the inlet 5 and force it into the outlet chamber 7 under pressure. The liquid will then pass through the openings 22 into the strainer casing 23 and through the strainer into the passage in the tubular shaft 16

10 which forms the outlet passage for the pump and may convey the liquid to any suitable point. The strainer 26 is constantly rotated at high speed and tends to throw off or deflect any solid particles in the liquid which may attempt to pass through the mesh covering 30. At the same time this centrifugal action incident to rotation of the strainer prevents collection of any solid matter on the

15 strainer and thereby obviates any stoppage of the flow of the liquid.

The pressure in the outlet chamber forces the pinion 14 tight against the hardened washer 19 which is in turn forced into tight contact with the wall of the casing section

20 A so as to retard any leakage around the shaft 16. At the same time, a suction is created in the opening 17 by the passage 21 which further retards any leakage through

25 the opening 17. The gland 20 provides an additional packing to prevent leakage around the shaft 16.

Another important feature of my invention is the mounting of the gear pistons 3 and 4 in the casing. As shown in Figures 3, 4, and 8, a stub shaft 31 for each gear piston is journaled in corresponding recesses 32 and 33 in the respective casing sections A and B. Each stub shaft has a central collar 34, the median portion 35 of the periphery of which is substantially cylindrical and coaxial with the stub shaft. The other portions 36 at opposite sides of the portion 35 of the periphery of the collar recede away

30 therefrom toward the axis of the shaft. Each gear piston has a central opening 37 of a diameter slightly greater than that of the median portion 35 of the corresponding stub shaft and of a length substantially greater

35 than the width of said median portion as clearly shown in Figure 8 of the drawings. This construction provides for a limited tilting movement of the gear piston into planes oblique to the axis of the corresponding stub

40 shaft so that the teeth of the gear pistons can adjust themselves to each other and the sides of the pistons may adjust themselves to the inner walls of the casing. This avoids chattering incident to the improper meshing of

45 the gear teeth, or jamming of the gears upon

the casing, or binding of the stub shaft 31 in the casing. It has been found that with such a construction the pump is substantially noiseless in operation and extremely efficient. The gear pistons in effect float in the pump chamber, but they are preferably keyed to the respective stub shafts 31 as by means of cylindrical pins 38 projecting from the peripheries of the collars 34 and loosely fitting keyways 39 in the gear pistons. This causes rotation of the stub shaft and provides against jamming of the peripheries of the gears against the walls of the pump chamber 2.

While I have shown and described the invention as embodied in certain details of construction it should be understood that this is primarily for the purpose of illustrating the principles of the invention and that many modifications and changes may be made in the details of construction without departing from the spirit or scope of the invention.

Having thus described my invention, what I claim is:

1 A rotary pump comprising a main casing formed of two complementary sections secured together, one of which is recessed to form a pump chamber, an inlet chamber and an outlet chamber between them, the outlet chamber having outlet openings through one of said sections, an outlet casing removably secured to the exterior of the second-mentioned section over said outlet openings, a plurality of intermeshing gear pistons journaled in said pump chamber to force liquid from said inlet chamber into said outlet casing, a tubular drive shaft having one end arranged in said outlet casing and the other end projecting from the main casing, a pinion on said drive shaft meshing with one of said gear pistons, and a strainer removably secured upon and covering the end of the drive shaft within said outlet casing to rotate with said drive shaft.

GEORGE H. MESSER.
